UNITED STATES PATENT OFFICE.

FRANCIS XAVIER FAHNDRICH, OF YOUNGSTOWN, OHIO, ASSIGNOR TO EDMUND FAHNDRICH, OF YOUNGSTOWN, OHIO.

BOTTLE-PUZZLE.

1,020,031.

Specification of Letters Patent.

Patented Mar. 12, 1912.

Application filed October 9, 1911. Serial No. 653,628.

To all whom it may concern:

Be it known that I, FRANCIS XAVIER FAHNDRICH, citizen of the United States, residing at Youngstown, in the county of 5 Mahoning and State of Ohio, have invented certain new and useful Improvements in Bottle-Puzzles, of which the following is a specification.

The present invention relates to what may 10 be termed a bottle puzzle, a number of disconnected and disjoined elements being provided which are adapted to be inserted through the contracted neck of a transparent container and thereafter assembled 15 within the container so as to form a symbolic or ornamental group, novel means being provided for closing the mouth of the container to retain the elements therein.

The object of the invention is to provide 20 a device of this character which is very fascinating and entertaining, which has an educational value, and which is ornamental and attractive in appearance.

With this and other objects in view, the 25 invention consists in certain novel combinations and arrangements of the parts as will more fully appear as the description proceeds, the novel features thereof being pointed out in the appended claims.

30 For a full understanding of the invention, reference is to be had to the following description and accompanying drawing, in which:—

Figure 1 is a detail view showing all of 35 the various parts detached, the bottle or container being shown in section, and Fig. 2 is a vertical longitudinal sectional view through the container with the various elements properly assembled therein.

40 Corresponding and like parts are referred to in the following description and indicated in all the views of the drawing by the same reference characters.

In carrying out the invention a bottle or 45 transparent container 1 is provided, the said bottle being formed with a contracted mouth 2. A number of normally disjoined elements are provided which are adapted to be inserted singly through the contracted 50 mouth 2 and thereafter assembled within the container 1 so as to form an ornamental or symbolic group. In the present instance the various elements after being assembled, as indicated in Fig. 2, form a display group 55 which is symbolic of the crucifixion. A pair

of intersecting cross bars 3 and 4 are first inserted into the container 1 and assembled on the bottom thereof, the said cross pieces being suitably notched at their intersection, as shown at 5, so as to provide a smooth 60 joint and rest firmly upon the bottom of the container. These cross pieces are preferably of such a length that the ends thereof engage the sides of the container, thereby forming a base upon which the remaining 65 elements can be positioned.

A hat pin or similar member may be employed for manipulating the elements within the container, and the various elements may have a small quantity of glue or other 70 adhesive material applied to suitable portions thereof so that the said elements will be retained in their proper places. The upright standard 6 of the cross may next be inserted in position, the lower end of the 75 standard being formed with a pin 7 which engages the cross pieces 3 and 4 at the intersection thereof, and the said standard being provided at a point toward the upper end thereof with a suitable notch 8 for engagement with a corresponding notch 9 in the cross arm which is subsequently placed in position.

The member 11 which is pendent from 80 one end of the cross arm 10 is symbolic of the lantern which was carried into the garden, while the member 12 which is pendent from the opposite end of the cross arm is symbolic of the whip with the many lashes. The member 13 which rests upon the top of 90 the cross arm at one end thereof represents the vinegar cup, while a hammer 14 and pincers 15 rest upon the top of the cross arm at the opposite end thereof. A ladder 16 leans against the front of the cross, and 95 upon opposite sides of the ladder are the spear 17 and the reed 18 with the sponge 19 at the upper end thereof. Also resting upon the base are the members 20, 21 and 22 which are symbolic of the cock which crew 100 upon the denial of Peter, the dice with which the multitude cast lots for Christ's garments, and the skull and cross bones, respectively. As previously stated, these various elements are all inserted singly 105 through the contracted mouth of the container and then properly assembled therein by means of some instrument such as a piece of wire or a hat pin.

After the elements have all been properly 110

positioned, the mouth of the container is closed by a stopper 23 having an extension 23^a at the inner end thereof which projects into the container and engages the upper 5 end of the standard 6. A locking key 24 extends through a transverse opening in the extension 23^a so as to prevent withdrawal of the stopper, and the manner in which this locking key is placed in position is some- 10 what of a mystery to a casual observer. By reference to Fig. 1, however, it will be observed that the stopper 23 is formed with a transverse opening 25 and also with a longitudinal opening 26 which intersects the 15 transverse opening and extends through to the upper or outer end of the stopper. A cord 27 is designed to be inserted through the longitudinal opening 26 and have the end thereof drawn through the transverse 20 opening 25 and secured to the middle portion of the key 24. This key is preferably slightly curved and is formed at one end thereof with a suitable nick 28 adapted to engage an intermediate portion of the cord. 25 The key is dropped into the container in advance of the stopper 23, and after the stopper has been seated in position the cord 27 is pulled through the opening 26. Owing to the fact that this cord has been engaged 30 by the nick 28, the end of the key 24 will be drawn into the opening 25 until the nick 28 comes opposite the longitudinal opening 26. A continued pull upon the cord will then draw the cord out of the nick so as to 35 cause the same to pull the key through the transverse opening until the middle portion thereof to which the cord is secured is under the longitudinal opening 26. The cord may then be pulled out or broken and the 40 upper end of the longitudinal opening 26 closed with a suitable plug. The stopper 23 can not be withdrawn without breaking the key 24 after the said key has once been drawn into position, and the various elements are held securely within the container 45 by means of the stopper.

Having thus described the invention, what I claim as new and desire to secure by Letters Patent, is:—

50 1. In a device of the character described, the combination of a container formed with a contracted mouth, a series of disjoined elements adapted to be inserted singly through the contracted mouth and thereafter assembled within the container into a connected group, and a stopper for closing the mouth of the container and holding the elements in position.

60 2. In a device of the character described, the combination of a container formed with a contracted mouth, a series of disjoined elements adapted to be inserted singly through the mouth of the container and thereafter

assembled therein into a connected group, a stopper for closing the mouth of the container, and a key for retaining the stopper in position. 65

3. In a device of the character described, the combination of a container formed with a contracted neck, a series of disjoined elements adapted to be inserted singly through the contracted neck and thereafter assembled within the container into a connected group, a stopper formed with a transverse opening adapted to close the mouth of the container, a key, and means for positioning the key within the transverse opening of the stopper after the stopper has been placed in position. 70

4. In a device of the character described, the combination of a container formed with a contracted neck, a series of disjoined elements adapted to be inserted singly through the contracted neck and thereafter assembled within the container into a connected group, a stopper adapted to be inserted in the mouth of the container so as to retain the elements in position, the said stopper being formed with intersecting longitudinal and transverse openings, a cord inserted 85 through the longitudinal opening and extending through one end of the transverse opening, and a key having the end of the cord secured to an intermediate portion thereof and formed in one end thereof with 90 a nick adapted to engage the cord so that the key can be drawn into the transverse opening by pulling upon the cord. 95

5. In a device of the character described, the combination of a container formed with a contracted neck, a series of disjoined elements adapted to be inserted singly through the contracted neck and thereafter assembled within the container into a connected group, a stopper adapted to be inserted in the mouth of the container and formed with an extension adapted to project into the container and engage one of the elements, the said extension of the stopper being formed with intersecting transverse and longitudinal openings, a cord inserted through the longitudinal opening and extending through one end of the transverse opening, and a key having the inner end of the cord secured to an intermediate portion thereof and formed in one end thereof with a nick for engaging the cord so that the key can be drawn into the transverse opening by pulling upon the cord. 100

110 In testimony whereof I hereunto affix my 115 signature in the presence of two witnesses.

F. XAVIER FAHNDRICH.
